(57) **CLAIM**

The ornamental design for a key chain and personal protection design, as shown and described.

DESCRIPTION

FIG. 1 is an upper perspective view of a key chain and personal protection design showing my new design.

FIG. 2 is a top view of a key chain and personal protection design showing my new design.

FIG. 3 is a bottom view of a key chain and personal protection design showing my new design.

FIG. 4 is a right side view of a key chain and personal protection design showing my new design.

FIG. 5 is a left side view of a key chain and personal protection design showing my new design.

FIG. 6 is a front end view of a key chain and personal protection design showing my new design.

FIG. 7 is a rear end view of a key chain and personal protection design showing my new design; and,

FIG. 8 is a cross sectional view taken along line 8—8 of FIG. 2.

Any shading and cross-hatching are not features of the design but are utilized to illustrate the surface contours of the key chain and personal protection design in the drawings.
